UNITED STATES PATENT OFFICE.

NORMAN L. ROULET, OF TOLEDO, OHIO.

DESIGN FOR A PIN, BUTTON, BADGE, EMBLEM, OR ARTICLE OF SIMILAR NATURE.

Application filed January 29, 1923. Serial No. 5,020. Term of patent 7 years.

To all whom it may concern:

Be it known that I, NORMAN L. ROULET, a citizen of the United States, and a resident of Toledo, in the county of Lucas and State of Ohio, have invented a new, original, and ornamental Design for a Pin, Button, Badge, Emblem, or Article of Similar Nature, of which the following is a specification, reference being had to the accompanying drawing, forming a part thereof.

In the drawing Fig. 1 is a plan view of a pin, button, badge, emblem, or article of similar nature showing my new design, and Fig. 2 is an edge view thereof.

I claim:-

The ornamental design for a pin, button, badge, emblem, or article of similar nature substantially as shown.

NORMAN L. ROULET.
